COMBINED WATCHCASE AND WRISTBAND
CONNECTIONS THEREFOR

Robert A. Barré, New York, N. Y.

Application April 17, 1950, Serial No. 9,272

Term of patent 3½ years

(Cl. D42—8)

To all whom it may concern:

Be it known that I, Robert A. Barré, a citizen of the United States of America and a resident of the city of New York, county of Queens, and State of New York, have invented a new, original, and ornamental Design for a Combined Watchcase and Wristband Connections Therefor, of which the following is a specification, reference being had to the accompanying drawing, forming a part hereof, wherein:

Fig. 1 is a top plan view of the combined watchcase and wristband connections therefor, showing my new design with the wristband in closed position;

Fig. 2 is a similar view in disengaged position;

Fig. 3 is a side elevational view of the same with the wristband in a disengaged position;

Fig. 4 is also a side elevational view with the wristband in closed position; and

Fig. 5 is an end view of the watchcase only.

The essential features of my design are shown in full lines and the wristband is shown fragmentarily in Figs. 1, 2 and 4, for convenience of illustration.

I claim:

The ornamental design for a combined watchcase and wristband connections therefor, substantially as shown and described.

ROBERT A. BARRÉ.
